UNITED STATES PATENT OFFICE.

ALBEN E. LUNDELL, OF NEW YORK, N. Y., ASSIGNOR, BY MESNE ASSIGNMENTS, TO
WESTERN ELECTRIC COMPANY, INCORPORATED, A CORPORATION OF NEW YORK.

AUTOMATIC TELEPHONE-EXCHANGE SYSTEM.

1,246,125.

Specification of Letters Patent. Patented Nov. 13, 1917.

Application filed October 22, 1915. Serial No. 57,290.

To all whom it may concern:

Be it known that I, ALBEN E. LUNDELL, a citizen of the United States, residing at New York, in the county of Bronx and State of New York, have invented certain new and useful Improvements in Automatic Telephone-Exchange Systems, of which the following is a full, clear, concise, and exact description.

10 This invention relates to automatic telephone exchange systems, and more particularly to means for controlling the association of an operator's telephone set with a connecting circuit extending between calling and called lines.

According to the main feature of this invention, upon the extension of a connecting circuit to a called line, for instance a local subscriber's line, the operator's telephone set, which has been associated with the connecting circuit upon the extension of the calling line to said circuit, will be automatically disconnected therefrom, the automatic disconnection of said telephone set being prevented if the connecting circuit is extended to another called line, for instance to a line leading to a toll or recording operator's position.

In the drawings, Figure 1 represents diagrammatically the circuit arrangement for establishing connections between calling and groups of called lines; and Fig. 2 represents an operator's controlling arrangement for supervising the establishment of connections.

35 In the following, a description will be given of the manner in which a connection is established between a calling subscriber's station 1 and one group of lines, such as a called subscriber's line, and between station 1 and another group of lines, such as a line leading to an operator's position (for instance a toll or recording operator's position) at which a jack 3 is provided.

The subscriber at station 1, by removing his receiver from the switchhook, causes the displaying of a line signal (not shown) to attract an operator's attention, whereupon this operator extends this line to a connecting circuit 15 by inserting a plug 4 into a jack 5 in which the calling line terminates. A circuit is closed thereupon from grounded battery through a resistance 6, the sleeve contacts of jack 5 and plug 4, and the winding of a trunk holding relay 7 to ground. This relay closes a circuit

from ground through its armature and front contact, contact 8 and the power magnet of a sequence switch 9 to grounded battery. Under the control of a normal spring 10, sequence switch 9 is moved out of position 1 into position 7. It will be noted at this point that the sequence switch contacts shown within the dotted lines, drawn around sequence switches 9, 11, 12, 13 and 14, are controlled by these sequence switches respectively. As soon as sequence switch 9 reaches its position 7, the operator's telephone set 20 is connected with the connecting circuit, united with the calling line by means of plug 4 and jack 5, through sequence switch contacts 21 and 22, battery being supplied to the line through the windings of repeating coil 23, 24.

The operator having learned the number of the desired line, for instance the line leading to a substation 2, depresses on her keyboard the numerical designation of this line for adjusting a sender 25 adapted to control a train of automatic selector switches such as 26, 27 and 28. Only two keys 43 and 49 are shown in Fig. 2 of the drawings. Sending devices of this type are well known, and therefore the operation of the sending and controlling arrangement will not be described in detail. Such description may be found in Patent No. 1,168,319 to A. E. Lundell, patented January 18, 1916. Keys 43 and 49 are provided with an extra set of contacts 48 and 52, respectively, for the purpose to be hereinafter set forth.

When sequence switch 9 reached its position 7, a circuit was closed from ground through the armature and front contact of relay 7, sequence switch contact 30, the contact 31 and the power magnet of sequence switch 11 to grounded battery. Under the control of a normal spring 29, sequence switch 11 is moved out of position 1 into position 11. When the sequence switch passes through position 2, a circuit is closed from ground through sequence switch contact 32, conductor 33, a wiper 34 of a well-known cord finder 35 adapted to connect an operator's controlling and sending device with the selected connecting circuit, contact 36 of sequence switch 13 and the winding of a relay 37 to grounded battery. This relay becomes energized, and by attracting its right-hand armature closes a driving circuit for sequence switch 13 through contact 110

38 for moving this sequence switch out of position 1 into position 2. Relay 37 does not become deenergized when sequence switch 13 leaves its first position, a circuit 5 being closed from grounded battery through the winding of this relay, sequence switch contact 39, the left-hand contact and armature of relay 37, cord finder brush 40, conductor 41 and contact 42 of sequence switch 10 11 to ground.

The desired line belongs to a group, connections to which need not be supervised by the operator. She depresses key 43 for controlling the operation of the selectors.

15 Supposing that register 14 of the power driven sequence switch type is in position 6, a circuit is closed from ground through contact 48 of key 43, contact 44 and the power magnet of sequence switch 14, whereupon

20 switch 14 is moved under the control of its normal contact 45 out of position 6 into position 1. In this position of register 14 a circuit is closed from ground through contact 48 of key 43, sequence switch contact

25 46, contact 47 and the power magnet of sequence switch 13 to grounded battery for moving this switch out of position 2 into position 8. A circuit is closed now from ground through sequence switch contact 50,

30 contact 51 and the power magnet of the sender sequence switch 12 to grounded battery, and this switch is moved out of position 1 into position 2.

In position 2 of sequence switch 12 and 35 position 11 of sequence switch 11, the fundamental or controlling circuit is extended to selector switch 26, this circuit being traceable through sequence switch contact 55, conductor 56, cord finder brush 57, the windings of stepping magnet 58, the left-hand contact and armature of a relay 59, sequence switch contact 60, cord finder brush 61, conductor 62 and sequence switch contact 63.

40 Under the control of revertive impulses sent 45 from selector 26 to the stepping magnet 58, the sender is caused in the well-known manner to be stepped toward its normal position. After the setting of selector switch 26 in accordance with the first digit designated by

50 sender 25, relay 59 becomes energized in the well-known manner and opens at its left-hand contact the fundamental circuit, causing thereby the arresting of selector 26 on the selected row of terminals whereupon

55 switch 26 will automatically hunt for a free trunk in the selected group. Relay 59 closes also a driving circuit from ground through its right-hand armature and contact, contact 64 and the power magnet of sequence switch

60 12 to grounded battery for moving this switch out of position 2 into position 4, whereupon relay 59 again becomes deenergized and reestablishes the fundamental circuit, which is now extended through the

65 brushes of selector 26 to a trunk leading to

another selector 27. Selectors 27 and 28 are controlled in their setting operation in the same manner as was described in connection with selector 26 with the exception that selector 28 is adjusted in accordance with two digits for selecting the line leading to substation 2. After the sending out of each digit, relay 59 is energized and closes the above traced driving circuit for sequence switch 12, whereby after the setting of connector 28, sequence switch 12 will be moved out of its position 8 into position 9. A circuit is closed thereupon from ground through sequence switch contact 65, cord finder brush 66, conductor 67, contact 68 and the power magnet of sequence switch 11 to grounded battery, and this switch is moved out of position 11 into position 16. In position 16 of sequence switch 11 the talking circuit is established through sequence switch contacts 70 and 71, the called 80 85 substation being signaled in any well-known manner.

When sequence switch 11 leaves its position 11, contact 42 is opened and therefore 90 relay 37 becomes deenergized and closes a circuit from ground through its right-hand armature and back contact, contact 72 and the power magnet of sequence switch 13 to grounded battery for moving the sequence 95 switch out of position 8 into position 17.

A circuit is now closed from ground through the right-hand armature and back contact of relay 37, sequence switch contacts 73 and 74, conductor 75, and contact 100 76 and the power magnet of sequence switch 12 to grounded battery, whereupon sequence switch 12 is driven out of position 9 into its first position. The operator's sending and controlling apparatus being released to 105 normal, it may be employed now for controlling the establishment of another connection.

The establishment of the connection being completed, the operator's telephone set 110 20 is removed from the connecting circuit. A circuit is established from grounded battery through the power magnet and contact 80 of sequence switch 9, conductor 81, the left-hand back contact and armature of a 115 relay 82, conductor 83, sequence switch contact 84, conductor 75, sequence switch contacts 72 and 73, and the right-hand back contact and armature of relay 37 to ground. Sequence switch 9 is moved out of its listening-in position 7 into the listening-out position 11, and the operator's telephone set may thus be connected to other connecting circuits. When sequence switch 9 is moving toward its 11th position, circuit is closed 125 from ground through sequence switch contact 85, conductor 86, contact 87 and the winding of relay 82, conductor 88 and sequence switch contact 89 to grounded battery. Relay 82 becomes energized and closes 130

a locking circuit for itself through its contact 90. A circuit is now closed for driving sequence switch 13 out of position 17 into its normal position, this circuit extending 5 from ground through the right-hand armature and back contact of relay 87, sequence switch contacts 73 and 74, conductor 75, sequence switch contact 84, conductor 83, the left-hand armature and front contact of 10 relay 82, conductor 91, contact 92 and the power magnet of sequence switch 13 to grounded battery. When sequence switch 13 is moved out of position 17, relay 82 becomes deenergized.

15 Should the operator desire to disconnect her telephone set from the connecting circuit at any stage of the operation, by depressing a master listening-out key 93, she may cause sequence switch 9 to move out of 20 position 7 into position 11. If the operator after her set has been disconnected desires to listen-in again, she depresses a key 94, closing thereby a circuit through sequence switch contacts 95 for sequence switch 9, 25 causing the movement of this sequence switch out of position 11 into position 1, from which position it will be driven into position 7 due to the closure of the circuit extending from ground through the armature 30 and front contact of relay 7 and sequence switch contact 8.

When the parties have finished their conversation, the operator by pulling out plug 4 from jack 5 causes the deenergization of 35 relay 7, which in turn closes a circuit from ground through its armature and back contact, contact 95 and the power magnet of sequence switch 9 to grounded battery, causing the movement of sequence switch 9 out 40 of position 11 into position 1. The switches 26, 27 and 28 employed in the connection are restored to normal in the well-known manner.

Should the calling subscriber desire to obtain 45 a connection to a line leading to jack 3, which is at a toll operator's position, it is necessary that the connecting operator's telephone set remains connected to the selected connecting circuit for the purpose of making possible the recording of this toll call. The building up of the connection is accomplished in the same manner as described in the previously supposed case; now, however, the operator will have to depress key 50 49 for causing the proper setting of selector 26. Selector 26 extends through an idle trunk 100, the fundamental circuit through this trunk and a train of switches (not shown) to jack 3, whereupon a relay 101 is 55 energized due to the closure of a circuit extending from grounded battery through the winding of this relay, selector 26, sequence switch contact 70 to ground at repeating coil 23. This relay causes the actuation of a 60 signal 102 which remains operated until the

toll operator inserts her plug into jack 3, causing the energization of relay 103.

Supposing that switch 14 is in position 1 when the operator depresses key 49, a circuit is closed from ground through contact 52 70 of key 49, sequence switch contact 104 and the power magnet of sequence switch 14 to grounded battery, causing the movement of this sequence switch through position 5 into position 6, in which position the sequence 75 switch 13 is moved out of position 2 into position 8 in the same manner as it was above described, with the only exception that in this case the circuit extends from ground through key contact 52 and sequence switch 80 spring 105.

As soon as sequence switch 13 reaches position 4, a circuit is closed from ground through sequence switch contacts 106, 107 and 108, conductor 109, the winding of relay 82, conductor 88 and sequence switch contact 89 to grounded battery. Relay 82 becomes energized and closes a locking circuit through its right-hand armature, and therefore, upon the moving of sequence switch 90 12 to position 1, no circuit is found through sequence switch contact 84 and the left-hand back contact of relay 82 for moving the listening sequence switch 9 out of its listening- 95 in position. Because of the energization of relay 82, sequence switch 13 is moved out of its position 17 into position 1 in the same manner as above described, whereupon relay 82 becomes deenergized.

What is claimed is:

1. In a telephone system, a plurality of lines, connecting circuits and switches for interconnecting said lines, a telephone set, means actuated upon the association of one of said connecting circuits with a line for 105 uniting said telephone set thereto, automatic means for removing said telephone set from the circuit upon the completion of a connection from one line to a certain line, and means for preventing the operation of said 110 automatic means upon the completion of a connection from one line to another line.

2. In a telephone system, groups of lines, connecting circuits for connection thereto, a telephone set common to said connecting 115 circuits, a sequence switch for each connecting circuit, a controlling magnet for each switch, means whereby the controlling magnet of the sequence switch will be operated upon the association of a connecting circuit 120 with a calling line to connect the telephone set to said circuit, automatic means for again actuating said magnet to remove said set from the circuit upon the completion of a connection to a certain called line, and means 125 for preventing the repeated actuation of said magnet upon the completion of a connection to another called line.

3. In a telephone system, a plurality of telephone lines, an operator's position, a 130

- connecting circuit for connecting a calling line with a called line or with said position, a telephone set adapted to be united with said circuit, means operable upon the association of said connecting circuit with a calling line for connecting the telephone set to said circuit, automatic means operable upon the completion of a connection from a calling line to a called line for removing said set from said circuit, and means for preventing the operation of said automatic means upon the completion of a connection from a calling line to said operator's position.
4. In a telephone system, a plurality of lines, connecting circuits, switches for extending a connecting circuit to calling and called lines, a telephone set common to said circuits, a sending device for controlling the operation of certain of said switches, means automatically actuated when a circuit is extended to a calling line for joining the telephone set thereto, automatic means operated when said sending device has reached a predetermined stage in its control of the establishment of a connection to a certain called line for removing said telephone set from said circuit, and means for preventing the operation of said automatic means if the sending device reaches said predetermined stage in the control of a connection to another called line.
5. In a telephone system, a plurality of telephone lines, connecting circuits, means for connecting said circuits to calling lines, selector switches for extending said circuits to called lines, a telephone set, a switching device operated upon the extension of a circuit to a calling line for uniting said telephone set thereto, means for again actuating said device when the connection is extended to a certain called line to remove said set from said connecting circuit, and means for preventing the repeated actuation of said device when the connection is extended to another called line.
6. In a telephone system, a plurality of lines, connecting circuits for association with said lines, a telephone set common to said connecting circuits, electromagnetically operated means individual to each connecting circuit for automatically uniting said telephone set thereto when said circuit is associated with a calling line, a circuit common to said electromagnetically operated means, whereby said means will be actuated to remove said telephone set from a connecting circuit when the connection being established therefrom reaches a predetermined stage, and a relay for interrupting said circuit, whereby it will be rendered ineffective to cause the removal of said set from a connecting circuit when the connection being established therefrom is extended to a certain called line.
7. In a telephone system, a plurality of lines, a connecting circuit, means including selector switches for extending a connecting circuit to calling and called lines, a telephone set adapted to be connected to said circuit upon its extension to a calling line, manual means for controlling the extension of the connecting circuit by means of said switches to a called line, automatic means operative thereupon for removing said telephone set from said circuit, other manual means for controlling said switches to extend said connecting circuit to another called line, and means operative thereupon for preventing the actuation of said automatic means.
8. In a telephone system, a plurality of lines, connecting circuits, means including variably operable selector switches for extending a circuit to calling and called lines, a telephone set, means actuated when a circuit is extended to a calling line for joining the telephone set thereto, automatic means operated when said switches are controlled to select a certain called line and extend a calling line thereto for removing said telephone set from said connecting circuit, and means for preventing the operation of said automatic means if said switches are controlled to select another called line and extend a calling line thereto.
9. In a telephone system, a plurality of lines, connecting circuits and switches for interconnecting said lines, a telephone set, means for uniting said telephone set to a connecting circuit, automatic means for removing said telephone set from the connecting circuit upon the completion of a connection from one line to a certain line, and means for preventing the operation of said automatic means upon the completion of a connection from one line to another line.
- In witness whereof, I hereunto subscribe my name this 18th day of October, A. D. 1915.
- ALBEN E. LUNDELL.
